UNITED STATES PATENT OFFICE.

GEORGE T. VIVIAN, OF FLUSHING, NEW YORK.

STAGE-SHIP.

1,281,885.

Specification of Letters Patent. Patented Oct. 15, 1918.

Application filed October 19, 1916. Serial No. 126,507.

To all whom it may concern:

Be it known that I, GEORGE T. VIVIAN, a subject of the King of Great Britain, and a resident of Flushing, Long Island, in the 5 county of Queens and State of New York, have invented certain new and useful Improvements in Stage-Ships, of which the following is a specification.

The invention is an improvement in stage 10 ships, and its object is to provide a simple, safe and effective portable construction for obtaining a realistic pitching and rolling effect. This is accomplished by means of improvements and combinations hereinafter set 15 forth, and more particularly pointed out in the claims.

In the accompanying drawings:

Figure 1 is a perspective view of the ship; Fig. 2 is a side elevation of the double 20 cradle support;

Fig. 3 is a plan view thereof; and

Fig. 4 is a transverse section through the support.

The upper part 2 of the device is a suitable 25 structure simulating a ship of the particular type selected. The lower portion of this structure, below the "wave" line, constitutes one of the elements of the double cradle support hereinbefore referred to, being 30 mounted to rock laterally on an elongated lower cradle 3, which in turn may rock longitudinally on a base 4.

The base 4 may consist of a low oblong 35 frame, resting on casters 5, enabling it to be moved easily about the stage. Carried by this frame is a transverse shaft 6, whereon the cradle or immediate oblong frame 3 is pivotally supported at its center, the bottom of this cradle inclining upward in both 40 directions to permit its rocking. A longitudinal shaft 7 on the cradle 3 constitutes a pivotal support for the cradle bottom of the ship structure. In this instance the said bottom comprises a plurality of cross-plates 45 8 having oblique lower edges, these cross-plates having their central lower portions adjacent bearings 20 on cross-pieces 9 of the lower cradle, through which and through the plates the shaft 7 passes.

50 It will be noted that the cradle or inter-

mediate frame 3 lies close to the bottom frame and is in fact included between its longitudinal side members. The supporting structure as a whole is low and compact, well designed to withstand the strains of 55 operation, and incapable of being overturned, in spite of its portable character.

Buffer springs 10 and 11 are secured upon the base frame and the lower cradle, respectively, to cushion the longitudinal and lateral 60 rocking movements, these springs being normally free of the rocking members above and being compressed thereby toward the end of the throw in either direction, so as to overcome the momentum and start the 65 part back upon its movement in the opposite direction. The fact that the buffer springs are normally spaced from the parts with which they are to contact is desirable, in that the free rocking movements checked 70 toward their end closely simulate the actual motion of a vessel.

Lever and link mechanisms may be provided for operating the rocking members, the levers 12 and 13 being fulcrumed by 75 means of rock-shafts 14 and 15 on the base and connected by crank arms 16 and 17 and links 18 and 19 with the respective rocking parts. The lever 12 controlling the side motion is located behind the central part of 80 the ship. The other levers controlling the pitching motion may be preferably disposed near the ends. It is found in practice, however, that the levers 13 and the connected linkage may be dispensed with, the upper 85 structure being rocked by direct manual effort of stage hands concealed behind the ship. The lever 12, however, is of decided value in controlling the side motion.

It will be noted that in this ship the cradle 90 that produces the rolling movement is above and the pitching movement cradle below. This gives a longer radius for the pitching movement, which is of advantage in obtaining a realistic effect.

95

What I claim as new is:

1. A stage ship comprising in combination a bottom oblong frame mounted on rollers, an intermediate oblong frame lying close to the bottom frame and pivotally 100

supported thereon upon a central transverse axis, and a ship-like body supported upon the intermediate frame upon a longitudinal axis.

5 2. A stage ship comprising in combination a bottom oblong frame, an intermediate oblong frame lying close to and between

the longitudinal members of the bottom frame, a central transverse pivot connecting the frames, and a ship-like body supported upon the intermediate frame upon a longitudinal axis.

GEORGE T. VIVIAN.
